UNITED STATES PATENT OFFICE.

ADINO F. FILES, OF MAUMEE, OHIO.

DISPENSING MACHINE.

Application filed May 27, 1927. Serial No. 194,837.

My invention has for its object to provide, in connection with a dispensing machine for dispensing portions of a material, a mechanism for sealing and delivering the containers of each portion of the material dispensed from the machine. The invention particularly provides a means for forming and shaping the packages and for waterproofing and delivering the packages from the machine.

The invention may be contained in structures of different forms and may be used for different purposes. To illustrate a practical application of the invention, I have selected a dispensing machine to which my invention is applied for dispensing any material that may be composed of parts or particles of small size, as an example of the various constructions containing my invention. The structure referred to is described hereinafter and shown in the accompanying drawings.

Fig. 1 is a side view of the machine. Fig. 2 is a view of the top of the machine. Fig. 3 is a section taken on the plane of the line 3—3 indicated in Fig. 2. Fig. 4 is a section taken on the plane of the line 4—4 indicated in Fig. 2. Fig. 5 is a view illustrating a portion of the side of the machine. Fig. 6 is a view showing a modification of the machine. Fig. 7 is an end view of the machine. Fig. 8 is a perspective view of the cutter wheel and block. Fig. 9 is a perspective view in section of one of the squeeze rollers.

The particular machine embodying my invention and which is shown in the accompanying drawings is provided with a means for forming bags from two sheets of paper that are drawn from rolls as the paper is used in forming the bags. The machine is also provided with a means for dispensing quantities of a substance on one sheet of the paper while, at the same time, a glue or other cementitious material is placed on the second sheet. The machine is also provided with means for sealing or coating the bags thus formed.

The parts of the machine composing the mechanism are secured to the frame work 1 and the mechanism is operated by the electric motor 2, which drives the pulley wheel 3, the motor being connected with the pulley by the belt 4. A suitable clutch 6 may be provided for connecting the pulley wheel 3 with the shaft 7 by means of the handle 5. A pulley wheel 8 is located on one end of the shaft 7 and is connected to a pulley

wheel 9 by a belt 10. The pulley wheel 9 is located on the shaft 11 and the power for driving the operating parts of the mechanism is thus communicated from the motor 2.

The paper which is used in the formation of bags may be supplied to the machine in various ways, in the particular form of machine shown in the drawings, a roll of paper is supported at one end of the machine on a spindle 16 that may be located in the upper ends of a pair of brackets 17. The brackets 17 are bolted to the frame 1 and have outwardly extending arm portions 18 which support in their ends a shaft for the roller 19. The roller 19 and a roller 20 operate to guide the strip of paper 21 from the roll 15 in continuous alignment with regard to other portions of the machine and, at the same time, to produce proper tension in the paper. The strip of paper 21, as it is drawn from the roll 15, passes around the rollers 19 and 20 and under a reservoir 22 in which is maintained a supply of the substance to be dispensed. The reservoir 22 is provided with a vertically extending shaft 23 that may be formed integrally with a dispensing plate 24 which is located in the bottom of the reservoir 22. The shaft 23 is rotated by a pair of bevelled gear wheels 25 and the material is agitated and intermittently dispensed from the reservoir 22 through the dispensing plate 24 by rotation of the shaft 23. The bevelled gear wheels 25 are located on the shaft 23 and a shaft 26 supported on a bracket 27 located on the top of the reservoir 22. A gear wheel 28 is also located on the shaft 26 and is connected by a chain 29 to a pinion 30. The pinion 30 is keyed to the shaft 11 which is rotated by the pulley wheel 9. The quantities of the substance to be dispensed are deposited on the strip of paper 21 in pre-determined amounts and in relatively spaced positions on the strip of paper as it passes beneath the reservoir 22.

During the first operation of the machine or while the paper is passing under the reservoir 22, a second sheet of paper 34 is drawn from a roll 35 which may be supported on a spindle 36 located in the brackets 37. As the roll of paper 34 is drawn from the roll 35, it passes around a pair of rollers 38 and 39 which produce a tension in the strip of paper 34 when it is brought in contact with a glue imprinting roller 40 which places the glue upon the paper as the strip of paper moves on the surface of the roller

39. The glue imprinting roller 40 is provided with raised portions 41 which are substantially rectangular in outline and which carry the glue from a roller 42 located in 5 the glue box 43 to the paper as it passes between the rollers 39 and 40. The rollers 40 and 42 are operated by a chain of gear wheels 45, one of the gear wheels being located on the shaft 11. The paper is thus 10 imprinted with rectangular outlines of glue which are regularly spaced on its surface so that when the two strips of paper are pressed together a glue outline will surround the dispensed substance.

15. The two strips of paper, namely, the strip 34 having the imprints of glue and the strip 21 having the material dispensed thereon, meet as the two strips are drawn between a pair of rollers that are so constructed that 20 any air which might be left in the package as it is sealed will be pressed out at the same time that the glue is squeezed to completely seal the package. The rollers 50, 51, 52, and 53 are supported on shafts which have 25 their bearings in side plates which are secured to the frame of the machine. The shaft 11 on which the pulley wheel 9 is located also supports the roller 50 and a gear wheel 54. The gear wheel 54 is one of four 30 gear wheels which operate together to cause a timed relation between the rollers 50, 51, 52, and 53. The gear wheel 54 is in mesh with a gear wheel 55 which is also one of the chain of gear wheels 45. The gear wheel 35 55 rotates a gear wheel 56 by means of an idler pinion 57. The gear wheel 56 is in mesh with the gear wheel 58, thus the squeeze rollers 50 and 51 operate to squeeze the strips of paper together and also remove 40 any air from the center portion of the bag while the pressure rollers 52 and 53 again press the glue.

The squeeze rolls 50 and 51 are provided with rectangular recesses 60 formed in the 45 surfaces of the rollers so as to make the bags. The rollers 50 and 51 are provided with a soft gum rubber 61 located in the spaces 60 and as the strips of paper 34 and 21 pass between the rollers 50 and 51 50 the air is pressed from between the sheets and also the material may be flattened out. The surfaces of the rubber pads that are thus formed are located on the outside of the ridges formed by the recesses 60. The glue 55 which has been placed upon the strip of paper 34 by the glue roller 40 is spread upon edge portions of the strips of paper by the ridges 62 and 63 that are formed on the squeeze rollers 50 and 51 and the pressure 60 rollers 52 and 53. The ridges 63 of the rollers operate continuously along the edges of the strips of paper while the ridges 62 squeeze the glue outlines which form the 65 ends of the bag as these portions pass between the rollers.

In order to protect the dispensed substance against moisture, I have provided a means for applying a moisture proof material to the outer surfaces of the strip of paper. The material is applied while in a liquefied condition and when cool will operate to protect the substance contained within the bag. Any material having wax-like properties may be used. In the form of construction shown, paraffin is located in a suitable box 70 or container 70 that is supported on the frame 1 and heated by the element 71 which is secured to the bottom of the box 70. The heat element 71 may be controlled to melt the paraffin to varying degrees of liquefaction as may be desired with respect to the quality of paper used for forming the bags. The paraffin is carried from the box 70 by a roll 72 which places a coating of the liquefied paraffin on the outer surfaces of the strips of 80 paper. The roller 72 is supported on a shaft 74 which has its bearing in the bracket 37 and is rotated by a gear wheel 76 located on one end of the shaft 74. The paraffin is spread on the outer surfaces of the strip of 85 paper as it passes between the roller 72 and a soft rubber roller 73. The roller 73 operates, also, to distribute the paraffin over the upper surface of the paper and at the same time removes any surplus paraffin that 90 might otherwise accumulate as the strip of paper leaves the roller 72. The roller 73 is supported on the shaft 75 and is rotated by the gear wheel 77 which is in mesh with the gear wheel 76. The gear wheel 76 is in mesh with a large idler gear wheel 78 which is in mesh with the gear wheel 56. To quickly congeal the paraffin and thus prevent penetration of the paraffin to the inner 95 surfaces of the paper, a water pan 80 is located near the roller 72 so that, immediately after the paper has passed over the paraffin roller 72, it will be completely immersed in water as it passes under a 100 roller 81.

The roller 81 may be supported on a spindle 82, the ends of which are located in brackets formed in the side portions of the pan 80. After passing through the water pan 80, the strip of paper passes between a 115 pair of rollers which are so located with respect to the water pan 80 that any water remaining on the upper surface of the strip of paper will run back into the water pan. To wipe off any excess water without pressure on the paper, the upper roller 85 may be formed of a soft material, such as rubber, while the lower roller 86 is of some non-corrosive metal, preferably brass. These 120 rollers 85 and 86 are supported on the shafts 87 and 88 respectively and are rotated relative to each other by a pair of gears 89 and 90 which are keyed to the shafts 87 and 88. The gears 89 and 90 are rotated by a chain 91 which connects the pinions 92 and 93. 125

The pinion 93 is secured to the end of the shaft 71 so that the driving power for the gear wheels 89 and 90 is made through the chain 91, the gear wheels 92, 93, 76, 78, 56, 5 and 54, the gear wheel 54 being keyed to the shaft 11 which is rotated by the pulley wheel 9.

After the strip of paper has passed between the rollers 85 and 86, it is cut into 10 bags of uniform length by a series of knives 100 which are bolted to a member 101 which is formed on a shaft 102 and rotated by a gear wheel 103. The gear wheel 103 is in 15 mesh with a gear wheel 104 located on the shaft 88 on the end opposite the gear wheel 90. The gear wheels 104 and 103 are synchronized to operate in timed relation with other parts of the machine so that, as the knives 100 shear the strip of paper into individual 20 packages or bags, the shearing is made between the ends of the areas outlined by the glue. A knife edge plate 105 secured to a block 106 is located tangential to the cylinder described by the edges of the knives 25 100 in their rotation and the knives are arranged diagonally on the member 101 so that the shearing is made from one side of the strip of paper to the other as the knives 100 rotate. As the bags are cut from the continuous 30 strip of paper, they drop down the inclined surface of the block 106, and the inclined surface of the member 107 which is secured by bolts to the frame 1. The member 107 has an opening or mouth 108 which is sufficiently 35 large to allow for discharge of the packages as they reach the bottom of the member 107. The bags are caught in a U-shaped pan 110 and are caused to pile up in a uniform relationship by a plunger 111 which is operated to push the bag out of the mouth 108 of the member 107.

The head of the plunger 111 is located in an opening in the member 107 and the reciprocating movements of the plunger 111 are caused by a pinion 112 which meshes with the gear wheel 103. The diameter of the gear 103 may be determined so that its rotation is timed with respect to the movement of knives of the member 101. A link 113 is 45 pivotally connected to the pinion 112 and to produce reciprocatory movements of the plunger 111. The plunger 111 is caused to reciprocate in and out of the member 107 by the movement of a lever 114 connected to the lower end of the link 113. The lever 114 is supported on a rocker shaft 115 that is supported in brackets which are secured to the frame 1. A rocker arm collar 120 is located on the rocker shaft 115. One of the 50 rocker arms of the collar 120 is connected by a link 121 to the plunger 111 so that, as the shaft 115 is caused to move, the rocker arm 120 will cause the plunger 111 to reciprocate through the opening of the member 55 107. The other rocker arm of the collar

120 is pivotally connected to a finger member 125 which, by reason of the oscillating movement of the rocker arm 120, is reciprocated over the surface of a ratchet disc 126 which may be so located with respect to the shaft 115 that the arm 125 will move across the surface of one of the teeth of the ratchet disc 126 with each movement of the shaft 115, and thus intermittently rotate the disc as the arm 120 is oscillated by the shaft 115. The disc 126 is located on a shaft 127 that is supported in brackets 128 which extend downwardly from the frame 1.

Means may be provided for dividing the packages into groups of any desired number. Pins 129 project from the surface of the disc 126 and, as the disc 126 rotates, the pins 129 come in contact with a finger 130 and cause the downward movement of the finger 130. The finger 130 is supported on one end of a shaft 131 which supports a curved finger member 132 on its opposite end. The shaft 131 is supported in the bracket 133 which is secured to the frame 1 and, as the finger 130 is moved downwardly by the pins 129, the finger 132 will be caused to move in and out of an opening formed in the side of the member 107. This movement of the finger 132 may be timed relative to the plunger 111 so that, when the plunger 111 has reached the limit of its outward movement, the finger 132 will move inwardly with respect to its relation to the plunger 111. Thus, as the package is being pushed outwardly by the plunger 111, the finger 132 will act upon one edge of the bag to move it from alignment with the bags which have preceded this particular bag on the pan 110 and thus divide the bags into groups as may be desired for packing the bags in a certain number of lots for shipment. The number of bags in each group may be increased or decreased by the number of pins which are located in the disc 126.

The form of construction shown in Fig. 6 is a modification of the machine wherein a printing frame 150 is secured to the frame 1 and the brackets 17 which support the roll of paper 15 may be secured to the top of the frame 150. By providing the printing frame, the strip of paper 21 may have any desired subject matter printed on one surface. A roller 151 is supported in the rear of the frame 150 so that, as the paper 21 passes between the printing rolls, the printing will be located on the lower side of the paper with respect to the reservoir. The frame 150 may also be provided with a roller 152 which will raise the paper 21 to the horizontal plane of the plate 153 over which it is moved. The operating parts of the printing frame are rotated by means of a chain 160 which connects a pair of pinions 161 and 162. The pinion 162 is located on the shaft 163 that may have bearing in one of

the brackets 164 which support the glue box 43. The shaft 163 also supports the gear wheel 165 which is meshed with the pinion 166 keyed to the shaft 11. The shaft 11, being rotated by the pulley 109, will thus rotate the gears 163 and 165. This will produce rotation of the gear 162 which will operate the printing press. The press rolls (not shown) are supported on a pair of shafts 170 and 171 which have located on their ends the gears 173 and 174. The shaft 170 also supports the pinion 162 so that, as the pinion 162 is rotated, the gears 173 and 174 will rotate the printing rollers and thus 15 imprint the desired matter on the sheet 21. The ink for the type, located on the upper one of the printing rollers, is supplied from a box 176 and is distributed to the type from the train of rollers 177.

20 I claim:

1. In a dispensing machine having means for dispensing portions of a material in spaced relation on a strip of paper, means for feeding a pair of strips of paper through 25 the machine, means for imprinting outlines of cementitious material on the other of the strips, squeeze rollers, one of the squeeze rollers having a cushioned surface for squeezing the air from and flattening the 30 material located between the said strips.

2. In a dispensing machine having means for dispensing portions of a material in spaced relation on a strip of paper, means for feeding a pair of strips of paper through 35 the machine, means for imprinting outlines of cementitious material on the other of the strips, a pair of squeeze rollers having soft rubber on their surfaces for pressing the strips together and flattening the material 40 to remove air from between the strips.

3. In a dispensing machine having means for dispensing portions of a material in spaced relation on a strip of paper, means for feeding a pair of strips of paper through 45 the machine, means for imprinting outlines of cementitious material on the other of the strips, a pair of squeeze rollers having soft rubber on their surfaces for pressing the strips together and flattening the material to 50 remove air from between the strips, the rollers having ridges for pressing the strips along the outlines of cementitious material.

4. In a dispensing machine having means for dispensing portions of a material in spaced relation on a strip of paper, means for feeding a pair of strips of paper through the machine, means for imprinting outlines of cementitious material on the other of the strips, a pair of squeeze rollers having soft 55 rubber on their surfaces for pressing the strips together and flattening the material to remove air from between the strips, the rollers having ridges for pressing the strips along the outlines of cementitious material, 60 the outer surfaces of the rubber having a

radius greater than the radius of the outer surfaces of the ridges.

5. In a dispensing machine having means for dispensing portions of a material in spaced relation on a strip of paper, means for feeding a pair of strips of paper through 70 the machine, means for securing the strips of paper together to enclose the portions of the material dispensed, means for distributing a wax-like material over the outer surfaces of the said strips. 75

6. In a dispensing machine having means for dispensing portions of a material in spaced relation on a strip of paper, means for feeding a pair of strips of paper through 80 the machine, means for securing the strips of paper together to enclose the portions of the material dispensed, means for distributing a heated wax-like material over the outer surfaces of the strips, and means for 85 chilling the said wax-like material.

7. In a dispensing machine having means for dispensing portions of a material in spaced relation on a strip of paper, means for feeding a pair of strips of paper through 90 the machine, means for securing the strips of paper together to enclose the portions of the material dispensed, a container for a wax-like material, a heating element for heating the material, a roller having a portion located below the level of the liquefied wax-like material and located on one side of the strips, a second roller located on the opposite side of the said strips and extending over the edges of the said strips, and in 95 contact with the first roller, the said rollers operating to coat the outer surfaces of the said strips with the liquefied wax-like material. 100

8. In a dispensing machine, having means for dispensing portions of a material in spaced relation on a strip of paper, means for feeding a pair of strips of paper through the machine, means for securing the strips of paper together to enclose the portions of 105 the material dispensed, a container for a wax-like material, a heating element for heating the material, a roller having a portion located below the level of the liquefied wax-like material and located on one side 110 of the strips, a second roller having soft rubber on its surface and located on the opposite side of the said strips from the first roller and in contact with the surface of the strips and with the surface of the first 115 roller, the said rollers for distributing a liquefied wax-like material over the outer surfaces of the strips. 120

9. In a dispensing machine having means for dispensing portions of a material in spaced relation on a strip of paper, means for feeding a pair of strips of paper through the machine, means for securing the strips of paper together to enclose the portions of 125 the material dispensed, a container for a 130

- wax-like material, a heating element for heating the material, a roller having a portion located below the level of the liquefied wax-like material and located on one side of 5 the strips, a second roller located on the opposite side of the said strips and extending over the edges of the said strips, the said rollers operating to coat the outer surfaces of the said strips with the liquefied wax-like 10 material, a means for chilling the wax-like material to prevent movement of the liquefied wax-like material to the inner surfaces of the said strips.
10. In a dispensing machine having means for dispensing portions of a material in spaced relation on a strip of paper, means for feeding a pair of strips of paper through the machine, means for securing the strips of paper together to enclose the portions of 20 the material dispensed, a container for a wax-like material, a heating element for heating the material, a roller having a portion located below the level of the liquefied wax-like material and located on one side 25 of the strips, a second roller having soft rubber on its surface and located on the opposite side of the said strips from the first roller and in contact with the surface of the strips and with the surface of the first roller for 30 distributing a liquefied wax-like material over the outer surfaces of the strips, a means for chilling the wax-like material to prevent movement of the liquefied wax-like material to the inner surfaces of the said strips.
- 35 11. In a dispensing machine having means for dispensing portions of a material in spaced relation on a strip of paper, means for feeding a pair of strips of paper through the machine, means for securing the strips 40 of paper together to enclose the portions of the material dispensed, a container for a wax-like material, a heating element for heating the material, a roller having a portion located below the level of the liquefied 45 wax-like material and located on one side of the strips, a second roller having soft rubber on its surface and located on the opposite side of the said strips from the first roller and in contact with the surface 50 of the strips and with the surface of the first roller for distributing a liquefied wax-like material over the outer surfaces of the strips, a container for containing water, means for dipping the strips in the water as it leaves 55 the said rollers to chill the wax-like material.
12. In a dispensing machine having means for dispensing portions of a material in spaced relation on a strip of paper, means for feeding a pair of strips of paper through 60 the machine, means for securing the strips of paper together to enclose the portions of the material dispensed, means for distributing a heated wax-like material over the outer surfaces of the strips, a container for 65 water, and means for dipping the strips hav-
- ing the heated wax-like material into the water.
13. In a dispensing machine having means for dispensing portions of a material in spaced relation on a strip of paper, means for feeding a pair of strips of paper through the machine, means for securing the strips of paper together to enclose the portions of the material dispensed, means for distributing a heated wax-like material over the outer surfaces of the strips, a container for water, means for dipping the strips having the heated wax-like material into the water, and a cushion roller for surfacing the chilled wax-like material. 80
14. In a dispensing machine having means for dispensing portions of a material in spaced relation on a strip of paper, means for feeding a pair of strips of paper through the machine, means for imprinting outlines of cementitious material on the other of the strips, squeeze rollers for squeezing the strips together to remove air and flatten the material and to press the glue, a container for containing heated wax-like material, means for dipping the strips into the container. 85
15. In a dispensing machine having means for dispensing portions of a material in spaced relation on a strip of paper, means for feeding a pair of strips of paper through the machine, means for imprinting outlines of cementitious material on the other of the strips, squeeze rollers for squeezing the strips together to remove air and flatten the material and to press the glue, a container for containing heated wax-like material, means for dipping the strips into the container, and means for chilling the wax-like material on the outer surfaces of the strips. 90
16. In a dispensing machine having means for dispensing portions of a material in spaced relation on a strip of paper, means for feeding a pair of strips of paper through the machine, means for imprinting outlines of cementitious material on the other of the strips, squeeze rollers for squeezing the strips together to remove air and flatten the material and to press the glue, a container for containing heated wax-like material, means for dipping the strips into the container, means for chilling the wax-like material on the outer surfaces of the strips, and means for shearing the strips between the outlines of the cementitious material. 105
17. In a dispensing machine having means for dispensing portions of a material in spaced relation on a strip of paper, means for feeding a pair of strips of paper through the machine, means for imprinting outlines of cementitious material on the other of the strips, squeeze rollers for squeezing the strips together to remove air and flatten the material and to press the glue, a container for containing heated wax-like material, means for dipping the strips into the container, 110
- 120
- 125
- 130

for dipping the strips into the container, means for chilling the wax-like material on the outer surfaces of the strips, means for shearing the strips between the outlines of the cementitious material, a trough for receiving the packages from the shearing means and a step-by-step means for displac-

ing packages separated by the pre-determined intermediate number of packages from the sheet of packages.

In witness whereof I have hereunto signed my name to this specification. ¹⁰

ADINO F. FILES.
